UNITED STATES PATENT OFFICE.

NELSON E. FUNK, OF MONTCLAIR, NEW JERSEY, ASSIGNOR TO R. HOE AND CO., OF NEW YORK, N. Y., A CORPORATION OF NEW YORK.

TRANSFER-PRINTING MACHINE.

1,123,724.

Specification of Letters Patent.

Patented Jan. 5, 1915.

Application filed April 7, 1911. Serial No. 619,464.

To all whom it may concern:

Be it known that I, NELSON E. FUNK, a citizen of the United States, residing at Montclair, county of Essex, and State of New Jersey, have invented certain new and useful Improvements in Transfer-Printing Machines, fully described and represented in the following specification and the accompanying drawings, forming a part of the same.

This invention relates to improvements in transfer printing machines.

In transfer printing machines of the rotary type, the transfer cylinder is, of course, arranged between the type or plate cylinder and the impression cylinder. Machines of this class include a throw-off mechanism, the purpose of which is to move the transfer cylinder out of contact both with the type or plate cylinder and with the impression cylinder, when a sheet fails to be fed between the transfer cylinder and the impression cylinder. If the transfer cylinder is left in contact with the type cylinder when a sheet is not passing through the machine, there is liability that too much ink will be set off onto the transfer printing surface, and if the transfer cylinder is left in contact with the impression surface, the design will be imprinted upon the blanket. In some transfer printing machines as heretofore constructed, the transfer cylinder is left stationary and the throw-off mechanism operates to move both the type or plate cylinder and the impression cylinder. This method of operation requires cumbersome and expensive mechanism for its operation. In another class of transfer printing machines, the throw-off mechanism operates to move the transfer cylinder, the type and impression cylinders being held stationary, the throw-off mechanism including eccentric bearings for the transfer cylinder shaft, these bearings being mounted in the usual stationary boxes. While this method of operation has the advantage of moving only a single cylinder, it is objectionable because the cylinder shaft moves in the arc of a circle and this requires that the center of the transfer cylinder shaft shall be located well to one side of a line connecting the centers of the printing and impression cylinders. In most printing machines, however, it is desirable that the centers of the printing, transfer and impression cylinders be located

substantially in the same straight line, or as nearly in the same straight line as possible, and in some classes of machines, such an arrangement is practically necessary on account of the character of stock to be printed. 60

The present invention has for its object to produce an improved mechanism for moving the transfer cylinder of transfer printing machines of the rotary type out of contact with the printing and impression cylinders, 65 this mechanism being of such a character as to enable the centers of all the cylinders to be arranged nearly in the same straight line.

With this and other objects in view, the invention consists in certain constructions 70 and in certain parts, improvements and combinations as will be hereinafter fully described and then specifically pointed out.

Referring to the drawings which illustrate one embodiment of the invention: Figure 1 is a side elevation of so much of a transfer printing machine embodying the invention as is necessary to an understanding thereof. Fig. 2 is an enlarged detail section on the line 2-2 of Fig. 1. Fig. 3 is a 75 similar section on the line 3-3 of Fig. 1. Figs. 4 and 5 are end elevations, partly in section, of certain parts of the throw-off mechanism, the two figures illustrating the mechanism in different stages of the operation. 85

Referring to the drawings, 1 indicates a part of the side frame in which the various cylinders are mounted, and 2 indicates the impression cylinder, this cylinder being mounted on a shaft 3 supported in suitable boxes 4 adjustable vertically to regulate the impression by means of the usual adjusting mechanism, indicated at 5. The type or plate cylinder is diagrammatically indicated at 6, and it will be understood that the center of the shaft of this cylinder is in the same vertical line as the center of the shaft 3. The transfer cylinder is indicated at 7. In machines embodying the invention the transfer cylinder will have its center substantially or nearly in the line connecting the centers of the plate and impression cylinders, and in order that this may be effected, the transfer cylinder will be mounted 90 in such a way that the throw-off mechanism, to be hereinafter described, will move it in substantially a right or straight line. While the construction by which this movement is effected may be varied, in machines embody- 105 110

ing the invention in its best form, the shaft 8 on which the transfer cylinder is mounted, will be supported in sliding boxes 8'. In the particular construction illustrated, these 5 sliding boxes are guided in their movement by ways 8" which are formed on the machine frame.

The particular mechanism for effecting the right or straight line movement of the 10 transfer cylinder may be varied within wide limits. In the particular construction illustrated, this mechanism includes (see Fig. 3) a rotary actuator comprising a shaft 9 suitably supported in the frame and extending 15 across the machine from side to side. As illustrated, this shaft has connected thereto by means of a feather 10 an eccentric sleeve 11 rotating in a collar 12 formed on one end of a connecting rod 13. This rod 13 has a 20 collar 14 formed on its other end, this collar comprising a bushing 15 in which the shaft 8 is mounted. The collar 14 is held in position by a cap 16 and the collar 12 by a flange 17 formed on the sleeve 11, the sleeve 25 being held in position by a cap 18. It will be understood that there is a sleeve and a connecting rod 13 with its collars on each side of the machine, but as the constructions are identical, only one side of the machine is 30 shown. It will be obvious that with this construction when the shaft 9 is rotated the boxes in which the transfer cylinder shaft is mounted will be given a right line movement for moving the transfer cylinder out 35 of contact with both the impression and type or plate cylinders.

The operating means for the actuator may be varied and will be varied according to the type of actuator employed. The means, 40 however, should be of such a character as to be under the control of the operator so that the machine may be tripped, that is, the transfer cylinder moved, when necessity therefor arises. In the particular construction 45 illustrated, the actuator shaft is provided with a collar 19 formed on the end of a sleeve 20 connected to the actuator shaft by means of the feather 10. This collar 19 is provided with notches 21, 22 which are 50 arranged to be engaged at proper times by a pawl 23 pivoted at 24 on a pawl carrying arm 25, extending from a toothed hub 26 loosely mounted on the shaft 9. The teeth on the hub 26 are in engagement with the 55 teeth of a segment 27 pivoted to a stud 28 on the frame of the machine. The inner end of this segment lever carries a roll 29 which runs in a cam groove 30 formed in a cam 31 fast to the end of the transfer cylinder. With this construction it will be 60 understood that as the transfer cylinder rotates the segment lever 27 will be rocked on its pivot and will effect an oscillating motion of the pawl carrying arm from the 65 position shown in Fig. 4 to the position

shown in Fig. 5. It will be further understood that if the pawl 23 is free to engage either the notch 21 or the notch 22 of the disk 19, it will effect a movement of the actuator shaft. In the normal operation of 70 the machine, however, the pawl carrying arm and the pawl move idly.

In the best constructions embodying the invention, the means for permitting the operation of the actuator may be varied and will 75 vary according to the means selected for effecting its operation. In the particular construction illustrated, there is provided a release mechanism comprising a collar 32 located alongside the disk 19 and embracing 80 the sleeve 20 on which the disk is formed, this collar having a high part 32' which extends beyond the periphery of the disk 19. This collar has formed in one piece with it a bent arm 33 to which is pivoted a connecting rod 34 extending through a guide fast to the inside of the frame of the machine. This rod is connected at its lower end to an arm 36 on a treadle shaft 37, the treadle on the shaft being marked 38. A spring 39 90 surrounds the rod 34 and holds it in such position that the high part 32' of the collar is opposite either the notch 21 or the notch 22 according to the position of the actuator shaft. The pawl 23 has a roll 23' fast on it 95 and when the high part 32' of the collar 32 is opposite either the notch 21 or 22, as shown, for instance, in Fig. 5, the roll 23' will ride up on this high part of the collar and keep the pawl from engaging the notch. 100 When, however, the operator depresses the treadle the collar is swung into the position shown in Fig. 4, in which position the pawl 23 is free to and will engage the notch 21 or 22, according to whichever one is in proper 105 position. The pawl having engaged the notched collar, will rotate the actuator shaft 9 and through the connections described move the transfer cylinder.

The machine should not be tripped except between printings, and in order to prevent the operator from tripping except at the proper time, the shaft 37 may be provided with an arm 40 to which is pivoted a rod 41, this rod having a slot 42 which engages a crank pin 43 on the end of the shaft 3.

A locking mechanism may be provided to prevent the actuator shaft from being accidentally moved. While this mechanism 120 may be varied, in the particular construction shown, the disk 19 may be provided with notches 44, 45 arranged to be engaged by a locking pawl 46 pivoted on a stud 47 in the frame of the machine. This pawl is in the form of a bell-crank and its arm 48 is connected to a spring rod construction 49 of the usual type. The unlocking of this locking mechanism may be effected by mechanism of a suitable type, it being un- 125 130

derstood that the mechanism will vary according to the type of lock employed. As shown, the pawl 46 is provided with a roll 50, which is arranged to engage the high 5 part 32' of the collar 32 before referred to. When the operator, therefore, steps upon the treadle and swings this collar, he not only uncovers a notch to be engaged by the pawl 23 but he also releases the locking 10 pawl.

It will be seen that the foregoing mechanism is an exceedingly effective one for accomplishing the purposes for which it is designed, and, further, that by moving the 15 transfer cylinder in a substantially right or straight line, the center of the cylinder can be brought nearly in line with the centers of the plate and impression cylinders. Theoretically, of course, the transfer cylinder 20 touches the other two cylinders along one line only, but practically, and especially in view of the fact that the transfer cylinder has a soft covering, it has considerable surface in contact with both cylinders. To 25 avoid any wiping action as the transfer cylinder is moved, therefore, its center should be located slightly to one side of the line which connects the centers of the other two cylinders.

Changes and variations may be made in the construction by which the invention claimed is carried into effect. The invention claimed, therefore, is not to be confined to the particular construction herein 35 described and illustrated in the accompanying drawings.

What is claimed is:—

1. In a transfer printing machine, the 40 combination with the type, transfer and impression cylinders, said cylinders having their centers in substantially the same straight line, of means operatively connected with the driving mechanism of the machine for giving the transfer cylinder 45 a right line movement to move it into and out of contact with the type and impression cylinders.

2. In a transfer printing machine, the 50 combination with the type and impression cylinders, of a transfer cylinder having its center located substantially in a line connecting the centers of the type and impression cylinders, sliding boxes in which the transfer cylinder is mounted, an actuator 55 for giving the sliding boxes a right line movement, and means including a tripping mechanism for operating the actuator.

3. In a transfer printing machine, the combination with the type, transfer and impression cylinders, of means including an 60 actuator for giving the transfer cylinder a substantially right line movement, a locking mechanism for the actuator, and a release mechanism for said lock.

4. In a transfer printing machine, the 65 combination with the type and impression cylinders, of a transfer cylinder, sliding boxes in which the transfer cylinder is mounted, an actuator for operating the sliding boxes, operating means for the actuator, 70 and locking and release mechanisms for the actuator.

5. In a transfer printing machine, the combination with the type and impression cylinders, of a transfer cylinder, sliding 75 boxes in which the transfer cylinder is mounted, an actuator, connections between the actuator and the sliding boxes, a lock for the actuator, a normally inoperative driver for the actuator, and a release mechanism for releasing the lock and rendering 80 the driver operative.

6. In a transfer printing machine, the combination with the type and impression cylinders, of a transfer cylinder, sliding 85 boxes in which the transfer cylinder is mounted, an actuator, connections between the actuator and the sliding boxes, a lock for the actuator, a normally inoperative driver for the actuator, a release mechanism 90 for releasing the lock and rendering the driver operative, and means under the control of the operator for operating the release mechanism.

7. In a transfer printing machine, the 95 combination with a type and impression cylinders, of a transfer cylinder having its center located substantially in a line connecting the centers of the type and impression cylinders, sliding boxes in which 100 the transfer cylinder is mounted, a rotary actuator, connections between the actuator and the boxes for giving the boxes a right line movement, and means under the control of the operator for effecting the operation 105 of the actuator.

In testimony whereof, I have hereunto set my hand, in the presence of two subscribing witnesses.

NELSON E. FUNK.
